UNITED STATES PATENT OFFICE.

JAMES P. GORDON, OF FLORENCE, COLORADO.

WASHING-MACHINE.

SPECIFICATION forming part of Letters Patent No. 703,913, dated July 1, 1902.

Application filed July 13, 1901. Serial No. 68,175. (No model.)

To all whom it may concern:

Be it known that I, JAMES P. GORDON, a citizen of the United States, residing at Florence, in the county of Fremont and State of Colorado, have invented a new and useful Washing-Machine, of which the following is a specification.

This invention relates to washing-machines, and has for its object to provide a machine which will in an expeditious and thoroughly effective manner cleanse clothes or other articles to be washed without in the least damaging them.

An important feature of the present invention is that the clothes or other articles in being washed are not subjected to any rubbing action, but merely to a squeezing or compressing action, which operates to force the water and suds through the clothes, and thereby rapidly remove the dirt therefrom.

One object of the invention is to provide means for holding a large number of small articles in positive contact with relation to the washing-cylinder during the operation of being washed, thereby to insure thorough cleansing of each article and to facilitate removal of the clothes in bulk when properly cleansed.

A further object is to provide for the ready association with the washing-cylinder of the clothes-holding means and for the disconnection of such means from the cylinder when desired.

With these and other objects in view, as will appear as the nature of the invention is better understood, the same consists of the novel construction and combination of parts of a washing-machine, as will be hereinafter fully described and claimed.

In the accompanying drawings, forming a part of this specification, and in which like numerals of reference indicate corresponding parts, I have illustrated a form of embodiment of my invention capable of carrying my ideas into effect, it being understood that the manner of construction and arrangement of parts shown may be varied or changed without departing from the spirit of the invention, and in these drawings—

Figure 1 is a view in perspective, exhibiting a washing-machine constructed in accordance with my invention, the upper section

of the washing-cylinder being thrown back to a position it will occupy when the washing-cylinder is to be removed. Fig. 2 is a view in transverse section. Fig. 3 is a view in longitudinal section. Fig. 4 is a perspective detail view of a clothes-holder in the nature of a net bag in which small articles, such as napkins, handkerchiefs, and children's clothes, are confined while undergoing the process of washing. Fig. 5 is a fragmentary detail view showing the catch for holding the sections of the washing-cylinder closed.

Referring to the drawings, 1 designates a semicylindrical casing constituting a tub which may be constructed of any suitable material, preferably of sheet metal. The tub is supported upon a frame comprising two side pieces 2, two end pieces 3, and supporting legs 4, secured to the end pieces, the side and end pieces being held assembled in this instance by tie-rods 5 passing through the end pieces and held associated therewith by nuts 6. The tub has its ends closed by heads 7 and is connected with the side pieces by having the upper portions of its sides outturned, as at 8, and secured to the side pieces by screws or nails 9. The tub is provided with a detachable cover 10, which operates to prevent splashing out of water when the machine is in operation, and also with a faucet 11, by which the tub may be emptied when desired.

Working within the tub is the washing-cylinder 12, comprising two heads or disks 13, connected by a plurality of rungs 14, these by preference being circular in cross-section. Each head comprises two sections hinged together, as at 15, in such manner as to permit the upper section to be thrown back to the position shown in Fig. 1, thereby to permit removal of the clothes-cylinder 16, suitable spring-catches 17, carried by the upper sections of the heads and engaging locking projections 18 on the lower sections of the heads, 95 serving to hold the two sections firmly assembled.

The clothes-cylinder 16 is composed of two disks or heads 19, connected by rungs 20, these rungs being also preferably circular in cross-section and to be spaced apart a sufficient distance to permit passage of water and suds between them, the clothes-cylinder being a cage-like structure adapted to roll with-

in the washing-cylinder and by its weight, added to that of the clothes which it carries, to effect squeezing or compressing of the clothes, thereby to effect proper cleansing. 5 The clothes-cylinder is devoid of supporting bearings of any character, the effective operation of the device being secured by having the clothes-cylinder, as stated, to roll within and with the washing-cylinder, and thereby 10 effect washing of the clothes without exerting a scrubbing or rubbing action on the clothes, but merely a squeezing and compressing action, with projection through the clothes of the suds and water. It will be apparent that 15 where the clothes are merely subjected to rolling or squeezing action there can be no damage done them under the operation of the machine, so that fabrics of the most delicate character may be washed without being torn 20 or without having the buttons detached therefrom. As will be observed by reference to Fig. 2, the rungs of the washing-cylinder are more closely assembled than those of the clothes-cylinder, the object of this arrangement being to present an effective washing-surface upon which the clothes may be pressed, while the space between the rungs of the clothes-cylinder will permit free circulation of water through the clothes and the 25 cylinder.

The washing-cylinder is supported within the tub by stud-shafts 21 and 22, each comprising a journal, and a plate 23, bolted or otherwise secured to the lower sections of the 30 heads 13, the journals to work in bearings formed in the end pieces 3 of the tub-supporting frame. The stud 22 projects beyond the end piece in which it works and carries a pulley 24, to be connected with any suitable 35 source of power through a belt or the like, and as this will be well understood illustration is deemed unnecessary. The form of machine herein exhibited is intended more particularly for laundry purposes where large 40 bulks of clothes are washed at one time, and for that reason the washing-cylinder is shown as driven by power through the pulley 24; but it is to be understood that the invention is adaptable to domestic purposes, to effect 45 which the proportions of the parts will be suitably reduced in size and the stud 22 will be provided with a crank for rotating the washing-cylinder.

As a matter of further and specific improvement I employ in connection with the washing-machine a clothes-holding bag 26 for containing small articles of wearing-apparel or the like to be washed. This clothes-holder is an open-work structure made of heavy netting, such as strong cord or the like. The bag is provided along its sides and edges with reinforcing strips 27—such as fabric or the like—and back of one of its edges with suitable fastening means for holding the blank 50 in bag-like form when folded. In this instance the means for holding the bag in folded position consists in providing one of the

side-reinforcing strips with buttonholes 28, to be engaged by buttons 29, secured near the edge of the opposite side; but it is to be understood that the invention is not to be limited to the employment of buttons and buttonholes as a means for effecting the purposes designed, as any other suitable form of fastening device for the purpose may be employed and still be within the scope of my invention. The bag is provided with a means for engaging one of the rungs of the clothes-cylinder, and in this instance it consists of a plate 30, secured to one end of the bag, as by being stitched or otherwise secured thereto, the plate being provided with hooks or curved projections 31 to engage with one of the rungs of the clothes-cylinder.

When the device is to be employed for washing clothes, the hinge-section of the washing-cylinder is thrown back to the position shown in Fig. 1, after which the clothes-cylinder is removed from the washing-cylinder in any suitable way, as by means of a block and tackle. (Not necessary to be shown.) The articles to be washed are then placed within the bag, and the hooks at the end of the bag are brought into engagement with one of the rungs of the clothes-cylinder and the bag 95 wrapped about the cylinder, after which the latter is lowered into place within the washing-cylinder. Water and soap in suitable quantities are now supplied to the tub and the hinge-section of the washing-cylinder is closed 100 and is held from opening by means of the catches 17, after which the cover 10 is placed on the tub. The washing-cylinder is now rotated at the desired rate of speed and in the direction that will cause the clothes-holding bag closely to hug the outer side of the clothes-cylinder, and as this latter cylinder will roll upon the bottom portion of the washing-cylinder it will be seen that the suds and water will be forced through the articles carried by 105 the bag and through the rungs of the clothes-cylinder, thereby, as before pointed out, effecting thorough washing of the articles. When the washing has been effected, the faucet 11 is opened and the dirty water allowed 110 to escape, after which the washing-cylinder is supplied with clean water for rinsing purposes, and when rinsing has been effected the faucet 11 is again opened to permit escape of the water. In the further operation of the machine the clothes are wrung partially dry, this 115 being effected by the squeezing or the pressing action between the rungs of the washing-cylinder and the clothes-cylinder, as before pointed out. When the wringing operation 120 is completed, the cover 10 of the tub is removed, the top section of the washing-cylinder is thrown back, the clothes-cylinder lifted out of the washing-cylinder, and the bag containing the washed clothes is removed and 125 dropped into the said top section. Another bag containing clothes is then attached to the washing-cylinder, as described, the latter is 130 then lowered in place within the washing-

cylinder, and the operations described are again repeated. By employing a plurality of these clothes-holding bags there will be no time lost in effecting washing, as while the 5 contents of one bag is being washed another one will be filled with soiled clothes.

The advantage accruing from the employment of the clothes-holding bag herein described is that a great number of small articles 10 may be washed at one time and be removed from the washing-cylinder at one operation, thereby saving time that is usually lost in taking out the loose articles separately. It is also further to be understood that the 15 invention is not to be limited to the precise construction and arrangement of the parts of the washing-machine herein shown nor to the precise construction and arrangement of the clothes-holding bag, as it will be obvious that 20 the various parts of these elements may be varied or changed as may be found necessary in the practical operation of the device and still be within the scope of my invention.

From the foregoing it is thought that the 25 construction, operation, and many advantages of the herein-described invention will be apparent to those skilled in the art without further description, and it will be understood that various changes in the size, shape, 30 proportion, and minor details of construction may be resorted to without departing from the spirit or sacrificing any of the advantages of the invention.

Although I have shown the rungs of the 35 washing-cylinder arranged at closer intervals than those of the clothes-cylinder, I also contemplate having the rungs of both cylinders arranged at equal intervals and comparatively close together.

40 What I claim is—

1. In a washing-machine, the combination with a tub, of an open-work washing-cylinder rotatably mounted therein, an open-work clothes-cylinder loosely supported upon the 45 inner periphery of the washing-cylinder, and

an open-work clothes-containing bag to embrace the clothes-cylinder, and provided at one end with hooks for connection therewith.

2. In a washing-machine, the combination with a tub, of an open-work washing-cylinder rotatably mounted therein, an open-work clothes-cylinder loosely supported upon the inner periphery of the washing-cylinder, and an open-work clothes-containing bag to snugly embrace the clothes-cylinder and formed from 50 a sheet of netting, having opposite edges provided with mutually-coöperating fastening devices, and one of its other edges being provided with hooks for engagement with the open-work clothes-cylinder. 55

3. In a washing-machine, the combination with a tub, of an open-work washing-cylinder rotatably mounted therein, an open-work clothes-cylinder loosely supported upon the inner periphery of the washing-cylinder, and 60 an open-work clothes-containing bag to snugly embrace the clothes-cylinder, and formed from a sheet of netting having its edges provided with marginal binding-strips, one of said strips being provided with buttonholes, 65 buttons provided upon the opposite portion of the netting corresponding to the buttonholes, and a plate loosely connected to one of the other edges and provided with hooks for engagement with the open-work clothes- 70 cylinder. 75

4. In a washing-machine, the combination with an open-work clothes-cylinder, of a clothes-confining bag provided at one end with hooks to engage with the clothes-cylinder, 80 the bag to be of a length to pass entirely around the cylinder and to overlap the hooks.

In testimony that I claim the foregoing as my own I have hereto affixed my signature in the presence of two witnesses.
